Primary Examiner — Darlington Ly

(74) Attorney, Agent, or Firm — Michael Best and Friedrich LLP

(57) **CLAIM**

The ornamental design for a hydraulic brake controller for straddle-type vehicles, as shown and described.

DESCRIPTION

1. Hydraulic brake controller for straddle-type vehicles

1.1 is a front elevation view of a hydraulic brake controller for straddle-type vehicles embodying our new design;

1.2 is a rear elevation view thereof;

1.3 is a top plan view thereof;

1.4 is a bottom plan view thereof;

1.5 is a right side elevation view thereof;

1.6 is a left side elevation view thereof;

1.7 is a front and right side perspective view thereof; and

1.8 is a rear and left side perspective view thereof.

The design is directed to a hydraulic controller of brake liquid pressure in a wheel cylinder of a straddle-type vehicle, such as, a motorcycle or a bicycle; the broken lines in the drawings illustrate portions of the hydraulic brake controller that form no part of the claimed design.

1 Claim, 7 Drawing Sheets
